UNITED STATES PATENT OFFICE.

LEO BOCK, JR., OF NEW YORK, N. Y.

RECORDING AND REPRODUCING SOUND-WAVES.

SPECIFICATION forming part of Letters Patent No. 364,472, dated June 7, 1887.

Application filed December 4, 1886. Serial No. 220,692. (No model.)

To all whom it may concern:

Be it known that I, LEO BOCK, Jr., a citizen of the United States, residing at New York, county and State of New York, have invented 5 certain new and useful Improvements in Recording and Reproducing Sound-Waves, of which the following is a specification.

In my application for Letters Patent, filed December 11, 1885, under Serial No. 185,364, 10 is described a method of producing and retransmitting records of electrical and mechanical impulses or vibrations, consisting in causing a beam of light controlled by the impulses or vibrations to fall upon an actinically-sensitized transparent film or plate, thereby 15 producing the desired record, then preparing from this negative record a circuit-controller in the form of a non-conducting perforated plate or film, and then retransmitting the 20 original impulses or vibrations by placing the perforated non-conducting plate between a metal bed and stylus and moving it relatively to the stylus, thus allowing the stylus to make contact with the metallic bed through the 25 perforations or openings in the non-conducting film or plate and cause to flow over the line electrical impulses or vibrations corresponding to those by which the record was originally produced.

Now, this invention, which is allied to the invention embraced in my before-mentioned application, insomuch as it embodies analogous processes and apparatus, has for its special object to record and retransmit articulate 35 speech; and it consists, mainly, in the production of a transmitting medium composed of a conducting material provided with variable-resistance paths corresponding to the amplitude and rate of the vibrations to be retransmitted.

The best means of accomplishing the object of this invention at present known to me consists, first, in causing a beam of light, which is actuated or controlled by the diaphragm of a telephonic instrument, to vibrate 40 on a moving film, plate, or sheet transversely to the direction of motion thereof, said plate or sheet being originally transparent, or subsequently made transparent; secondly, in producing in or on an actinically-sensitized 45 conducting medium variable-resistance paths corresponding to the record produced on the

film, plate, or sheet, by exposing to the action of light a suitably-prepared sensitized conducting medium under the transparent record, and by subsequent treatment and fixing process varying its conductivity in proportion to the amount of light which passed through the record on the transparent film, plate, or sheet; and, thirdly, in retransmitting the recorded vibrations over a line by passing the variable-resistance paths of the conducting medium between a brush or roller and a metallic bed included in circuit with an electric battery and the receiving-instrument, or preferably in circuit with a battery and the primary coil of an 65 inductorium, the secondary coil of which is included in the line-circuit with the receiving-instrument.

For the variable-resistance circuit controller I have devised a sensitized electric conducting film, plate, or sheet specially adapted to the purpose, consisting of a mixture of gelatine, glue, isinglass, or other organic matter, a dichromate salt, an electric conducting material in a finely-pulverized condition, as carbon, 70 graphite, metals, or their electric conducting compounds, and water or other suitable solvent.

In the accompanying drawings, to which I will now refer, I show so much of apparatus 75 adapted to the carrying out of my invention as is necessary for a full understanding of the same to be had.

Figure 1 represents in section the receiving and recording apparatus. Fig. 2 represents 80 part of a negative record produced in the receiving and recording apparatus. Fig. 3 represents part of a variable-resistance circuit-controller prepared from and being the counter or positive of Fig. 2; and Fig. 4 is a diagram view of the essential parts of the transmitting apparatus.

The transparent material upon which the record is made is represented as a strip, *a*, made sensitive to the action of light by any of 85 the well-known photographic processes. It passes around and is moved by the drum or cylinder *b*, which is rotated at a uniform speed by the clock-work or other motor, *c*. The dark box *d* protects the strip *a* from extraneous light and has fitted in its side the diaphragm *e*, adapted to be actuated by sound-

waves through the mouth *f*. This diaphragm *e* may also be considered as the vibrating part of a telephonic receiver if the sound-waves to be recorded originate at a distance from the 5 apparatus. This diaphragm *e* is caused to actuate the light-controlling device, which consists of a shield, *g*, provided with a fine hole, *h*, and carried on the end of the lever *i*, which is pivoted at its lower end, *i'*, to the bottom of 10 the dark box *d*, so as to be capable of oscillation at right angles to the direction of vibration of the diaphragm *e*. This lever *i* is connected to the center of the diaphragm *e* by the fine adjusting-screw *j*. The shield *g* covers an 15 opening, *d'*, in the end of the box *d*, and opposite this opening is located the source of light, *k*, the rays of which are preferably concentrated in the opening *d'* onto the shield *g*, which permits only such rays as can pass 20 through the hole *h* to enter the dark box. A suitable arrangement of mirrors and lenses *k' k²* may be used to direct the rays of light from the source *k* to the opening *d'*.

The rays of light which enter the dark box 25 *d* through the hole *h* of the shield *g* are, when the shield *g* is at rest, directed upon the center of the sensitized strip *a*. Now, as this strip *a* is moved at a uniform rate of speed and the shield *g* is rocked by the action of the dia- 30 phragm *e* thereon at right angles to the direction of motion of the strip, the hole *h*, during each complete vibration of the diaphragm, allows the lateral rays of light to impinge upon the strip *a* on both sides of the normal 35 central line, thus acting on the sensitive material of the strip in such a manner that when the same is developed by the ordinary photographic process a sinuous negative marking is produced thereon, as shown at Fig. 2, the 40 altitude of the sinuosities being in accordance with the amplitudes of the vibrations of the diaphragm, and their number or recurrence in accordance with the rates of the vibrations of the diaphragm. This strip *a*, as before 45 stated, is transparent, and from it is prepared the variable circuit-controller *l*, which is represented in Fig. 3 as the positive or counter- part of Fig. 2.

The strip *l* is composed of a mixture of 50 suitable organic material—as glue, gelatine, &c.; a dichromate salt—as of potassium, ammonium, &c.; a finely-pulverized electric conducting material—as carbon, metals, their conducting compounds, &c.; and water or other 55 solvent of the organic material, by which it is brought into condition to be intimately mixed with the dichromate salt and conducting-pow- der and to be molded or formed into the de- sired shape. The quantity of each of the ma- 60 terials in this composition may be varied to suit the exigency of the case; but for general use good results may be obtained by the fol- lowing proportions, viz: one hundred parts of gelatine dissolved in sufficient water to admit 65 of its being formed into thin sheets, sixteen parts of potassium dichromate, and fifty parts

of finely-pulverized carbon, intimately mixed with the dissolved gelatine before forming into sheets. A strip or sheet of this sensitized conducting material is exposed to light under 70 the negative record-strip *a*, and thus made insoluble by the combined action of the light and the dichromate salts on the organic matter, the insolubility being in proportion to the amount of light passing through the negative; so that the parts covered by the most opaque parts of the negative are the most removed or washed away in the subsequent washing process to which the strip or sheet is subjected. Now it will be observed that if 80 this strip *l* be interposed in an electric circuit by placing it between a metallic bed and a brush or roller adapted to cover the greatest width of the path of the sinuosities and be moved uniformly under the brush or roller, 85 the resistance of the circuit will be varied by the changes of conductivity of the path for the current through the part of the strip *l* covered by the sinuous markings.

In Fig. 4 is shown how the strip *l* is practi- 90 cally applied to reproduce by transmission over a telephone-line the original articulate sounds recorded in the receiving apparatus. In this view the strip *l* passes around and is moved by the drum or cylinder *m*, uniformly 95 rotated by the spring or other motor, *n*. The brush or roller *o* is caused to bear on the sinuous markings of the strip *l*, and is connected to one end of the primary coil of the inducto- 100 rium *p*, the other end of which is in contact with the drum *m*. Said primary circuit also includes the battery *q*. The secondary coil of the inducto- 105 rium is included in the line *r*, at the other end of which is the telephonic receiver *s*.

The principles of operation in this trans- 110 mitting apparatus are similar in all essential features to those of ordinary telephonic ap- paratus, the impulses in the secondary circuit in this case being induced by variations in the 115 resistance of the primary circuit automatically produced by the movement of the variable-re- sistance circuit-controller *l*.

It will be understood that the variable-resis- 115 tance path may be produced on the sensitized 120 conducting sheet, plate, or film in a direct manner, by exposing the same to the action of light-rays controlled or directed thereon by the vibrations of a diaphragm in the receiving and recording instrument, such as is shown in Fig. 1; and my invention contemplates such pro- 125 duction of the variable-resistance circuit-con- troller; but in most applications of the inven- 130 tion I prefer to first produce the record of sound-waves and therefrom produce the vari- able-resistance circuit-controller, especially when it is desired to retransmit the recorded sound-waves over several lines, by making the desired number of variable-resistance circuit- controllers from the one transparent negative record. This transparent negative may be re- 135 tained as a permanent record of the message

received and retransmitted and variable-resistance circuit-controllers prepared from it at any subsequent time.

The sinuous markings on the strip *a* may be increased in width by means of the lens *k*, placed between the shield *g* and the strip *a*, which deflects the rays passing through the hole *h*.

Having now described my invention, what I claim, and desire to secure by Letters Patent, is—

1. As a means for retransmitting recorded articulate sound-waves, a circuit-controller consisting of an electrically-conductive film, plate, or sheet having a sinuous variable-resistance path corresponding to the sound-waves.

2. The combination, with a circuit-controller consisting of an electrically-conductive film, plate, or sheet having on its surface a va-

riable-resistance path of sinuous form corresponding to sound-waves, of an electric circuit, including a metallic bed upon which said film, plate, or sheet is placed, and a brush or roller arranged to cover the variable-resistance path, and a telephonic receiving-instrument actuated by said circuit.

3. A circuit-controller composed of a gelatinous material, a dichromate salt, and a conductor of electricity in a finely-divided condition, having a variable-resistance path formed thereon.

Signed at New York, N. Y., December 1, 1886.
